(57) **CLAIM**

The ornamental design for a rack for compact disks, as shown and described.

DESCRIPTION

FIG. 1 is a front perspective view of a rack for compact disks showing my new design;

FIG. 2 is a rear perspective view of the rack for compact disks of FIG. 1;

FIG. 3 is a front elevational view of the rack for compact disks of FIG. 1;

FIG. 4 is a rear elevational view of the rack for compact disks of FIG. 1;

FIG. 5 is a right side elevational view of the rack for compact disks of FIG. 1;

FIG. 6 is a left side elevational view of the rack for compact disks of FIG. 1;

FIG. 7 is a top plan view of the rack for compact disks of FIG. 1; and,

FIG. 8 is a top plan view of an individual layer of the rack for compact disks of FIG. 1 taken along line 8—8 of FIG. 3, it being understood that the design for each layer of the rack for compact disks is identical thereto.
